(57) **CLAIM**

The ornamental design for a fluid testing base station, as shown and described.

DESCRIPTION

FIG. 1 is a perspective view of a fluid testing base station according to our new design;

FIG. 2 is a top elevation view of thereof;

FIG. 3 is a bottom plan view thereof;

FIG. 4 is a rear elevation view thereof;

FIG. 5 is a front elevation view thereof;

FIG. 6 is a left side elevation view thereof; and

FIG. 7 is a right side elevation view thereof.

FIG. 8 is a perspective view of a fluid testing base station according to another embodiment of our new design;

FIG. 9 is a top elevation view of thereof;

FIG. 10 is a bottom plan view thereof;

FIG. 11 is a rear elevation view thereof;

FIG. 12 is a front elevation view thereof;

FIG. 13 is a left side elevation view thereof; and

FIG. 14 is a right side elevation view thereof.

FIG. 15 is a perspective view of a fluid testing base station according to still another embodiment of our new design;

FIG. 16 is a top elevation view of thereof;

FIG. 17 is a bottom plan view thereof;

FIG. 18 is a rear elevation view thereof;

FIG. 19 is a front elevation view thereof;

FIG. 20 is a left side elevation view thereof; and,

FIG. 21 is a right side elevation view thereof.

The dash-dash broken lines showing in the views illustrate unclaimed portions of the fluid testing base station and form no part of the claimed design.

1 Claim, 15 Drawing Sheets
